(57) **CLAIM**

The ornamental design for a fan part, as shown and described.

DESCRIPTION

FIG. 1 is a perspective view of a grill fan part in accordance with our new design; and,

FIG. 2 is a front elevational view of the grill fan part of FIG. 1.

The broken line showing of a fan grill, housing and stand is included for the purpose of illustrating environmental structure and forms no part of the claimed design.

1 Claim, 2 Drawing Sheets

FIG. 1

FIG. 2
